(57) **CLAIM**

The ornamental design for a spate for thyroid surgery, as shown and described.

DESCRIPTION

FIG. 1 is a front left side perspective view of a spate for thyroid surgery in accordance with the new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The broken lines immediately adjacent to the shaded areas in FIG. 5 represent bounds of the design, with the lines themselves and the areas within them forming no part of the claimed design.
